UNITED STATES PATENT OFFICE

1,947,818

PUMP FOR PUMPING MOLTEN METAL

George Herbert White, Philadelphia, Pa., assignor to Patent Product Corporation of Chicago, a corporation of Delaware

Application July 7, 1930. Serial No. 465,912

1 Claim. (Cl. 22—70)

My invention relates to improvements in pumps for pumping molten metal and the like and has for one object to provide a new and improved form of pump which will be self cleaning. Other objects of my invention will appear throughout the specification and claim.

My invention is illustrated more or less diagrammatically in the accompanying drawing, wherein—

10 Figure 1 is a side elevation in part section of a pump and plunger;

Figure 2 is a side elevation of a modified form of plunger;

15 Figure 3 is a side elevation in part section of a modified form of cylinder and plunger;

Figures 4, 5 and 6 are similar views showing further modified forms.

Like parts are indicated by like characters throughout the specification and drawing.

20 When molten metal such as lead is cast by means of a pump such as used in connection with type setting machinery, die casting and the like, experience shows that there is a tendency for the pump piston and cylinder to clog or become foul from the presence of refuse such as metallic oxides and the like and periodically therefore it is necessary to withdraw the plunger from the cylinder to enable the plunger and cylinder to be cleaned.

30 This difficulty has to some extent been obviated in the past by providing a plurality of annular grooves in the piston or plunger. These annular grooves traveling along the cylinder with their sharp edges adjacent the cylinder wall tend to scrape off the deposit and increase the length of time during which operation can take place without cleaning but as soon as the annular grooves are filled with refuse the plunger must be withdrawn and the grooves 40 cleaned out.

I have discovered that if the plunger or the cylinder or both are provided with one or more spiral grooves extending throughout such part of the cylinder as will permit the groove to be exposed to both ends when pressure is applied, that some of the molten metal will leak back through such grooves and carry with it the deposit which would otherwise remain in the grooves and ultimately clog the pump. The leakage through these grooves is small enough so that it does not adversely affect the operation of the device but is sufficient to provide a wiping stream or flow through the spiral groove 55 whereby the material is washed out.

In Figure 1, A is a melting pot. It contains a mass of molten metal A¹. The lug A² and pin A³ indicate any suitable support for the pot. Immersed in the body of molten metal in the pot is a pump cylinder A⁴ having a discharge spout or passage A⁵ terminating in a discharge nozzle A⁶ which is adapted to be brought into register with the mold by any suitable means forming no part of my invention and not here shown. A⁷ is a port leading through the wall of the cylinder and communicating with the body of molten metal so that when the piston is withdrawn, the port is opened, molten metal flows in to fill the cylinder. When the piston moves forward 60 the port is closed first and thereafter pressure is applied by the piston or, plunger to the metal in the cylinder to cause it to be forced out through the pipe A⁵ and nozzle A⁶.

65 B is a rock arm adapted to be operated by any means not shown to cause piston movement. This rock arm is pivoted to a piston rod B¹ which piston rod in turn is pivoted to the piston B². B³ is a handle of wood or other suitable insulating material on the piston rod whereby 70 the piston rod and piston may be manipulated by hand when desired to withdraw them from working relation with the pump. In Figure 1, the inner wall of the cylinder is shown as being 75 smooth. The outer periphery of the piston has a single spiral groove B⁴ wound threadwise about the piston so as to provide sharp scraping edges in opposition to the cylinder wall and so as to provide an elongated spiral escape passage from the interior of the cylinder about the periphery 80 of the piston and between it and the cylinder communicating at its other end with the body of material in the pot.

85 In Figure 2, there are two spiral passages B⁵ B⁶ as a substitute for the single spiral passage B⁴ of Figure 1. In Figure 3 the spiral passage B⁷ is located in the single peripheral wall of the cylinder and in this case the piston is shown provided with a plurality of annular grooves B⁸. In Figure 4 the piston has the single 90 spiral groove B⁴ but the cylinder has an additional spiral groove B⁹ of the same pitch as the groove B⁴ and traveling in the same direction. In Figure 5, the spiral groove B⁴ on the piston is associated with a spiral groove B⁹ in the wall 100 of the cylinder but in this case the two grooves are wound in opposite directions. In Figure 6 there is associated with the groove B⁴ on the piston a groove B¹⁰ in the cylinder wound in the same direction but of different pitch. 105 110

Many other combinations of grooving might be provided depending upon circumstances but they all have this in common, that there is provided a sharp shouldered cleaning or refuse receiving groove and that groove whether in the cylinder or in the piston or in both is wound screw threadwise so as to provide a long spiral passage through which molten metal may flow when pressure is applied to the piston so that such molten metal at each piston stroke may tend to clean out and discharge from the piston and cylinder the fouling material or refuse which by the piston reciprocation is caused to be scraped off from the opposed piston and cylinder surfaces and deposited in the groove

I claim:

In combination, a melting pot, a cylinder projecting upwardly from the bottom of the pot and adapted to be entirely immersed in the molten metal, a cylindrical opening at the top, an intake port through the wall of the cylinder adjacent the bottom of the pot, a piston adapted to reciprocate in the cylinder, a tortuous passage bounded by the cylinder and the piston communicating with the space beneath the piston within the cylinder at one end and with the body of metal above the cylinder at the other end, the edges of the walls bounding the tortuous passage being sharp.

G. HERBERT WHITE. 90

CERTIFICATE OF CORRECTION.

Patent No. 1,947,818.

February 20, 1934.

GEORGE HERBERT WHITE.

It is hereby certified that the above numbered patent was erroneously issued to "Patent Product Corporation of Chicago, a corporation of Delaware," whereas said Letters Patent should have been issued to Chester A. Macomic, Chicago Illinois, said Macomic being assignee by mesne assignments of the entire interest in said invention, as shown by the records of assignments in this office; and that the said Letters Patent should be read with this correction therein that the same may conform to the record of the case in the Patent Office.

Signed and sealed this 3rd day of April, A. D. 1934.

F. M. Hopkins
